CLAIM

The ornamental design for a goggle with built in monitors and earphones, as shown and described.

DESCRIPTION

FIG. 1 is a top, front and right-side perspective view of a goggle with built in monitors and earphones, showing my new design;

FIG. 2 is a top, rear and left-side perspective view thereof, shown with earphones in the extended position;

FIG. 3 is a top, front and right-side perspective view thereof shown being worn with brow band raised and earphones being extended, the broken line showing is intended for illustrative purposes only and forms no part of the inventive design;

FIG. 4 is a front elevational view thereof;

FIG. 5 is a rear elevation view thereof;

FIG. 6 is a left-side elevational view thereof;

FIG. 7 is a right-side elevational view thereof;

FIG. 8 is a top plan view thereof; and,

FIG. 9 is a bottom plan view thereof.
